The Tea Spot, Inc, Tuffy Steeper, <http://theteaspot.com/tuffy-tea-stepper-steepware.html>, viewed Mar. 4, 2014.*Primary Examiner* — Marianne Pandozzi*Assistant Examiner* — Jae Liang(74) *Attorney, Agent, or Firm* — Florek & Endres PLLC(57) **CLAIM**

We claim the ornamental design for a tea infuser, as shown and described.

DESCRIPTION

FIG. 1 is a perspective view of the tea infuser of the present invention.

FIG. 2 is a front elevation of the tea infuser of the present invention.

FIG. 3 is a rear elevation of the tea infuser of the present invention.

FIG. 4 is a right side elevation of the tea infuser of the present invention.

FIG. 5 is a left side elevation of the tea infuser of the present invention.

FIG. 6 is a top plan view of the tea infuser of the present invention.

FIG. 7 is a bottom plan view of the tea infuser of the present invention; and,

FIG. 8 is an exploded perspective view of the tea infuser of the present invention.

The broken line showing in the figure drawings are included for the purpose of illustration and form no part of the claimed design.
